US00D767398S

(12) United States Design Patent (10) Patent No.: US D767,398 S
(45) Date of Patent:  Sep. 27, 2016

(54) PACKAGE

(71) Applicant: HISAMITSU PHARMACEUTICAL CO., INC., Tosa-shi, Saga (JP)

(72) Inventors: Masaki Miyazaki, Tokyo (JP); Shigeo Kusumi, Tokyo (JP)

(73) Assignee: HISAMITSU PHARMACEUTICAL CO., LTD., Tosa-shi, Saga (JP)

() Term: 14 Years

(21) Appl. No.: 29/512,314

(22) Filed: Dec. 18, 2014

(51) LOC (10) Cl. 09-99

(52) U.S. Cl.

USPC D9/499

(58) Field of Classification Search

USPC D9/414, 419, 432, 434, 457, 499, 667;
D14/485, 487, 489; 206/495

CPC B65D 2203/02; B65D 5/4233

See application file for complete search history.

CLAIM

The ornamental design for a package, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front elevational view of the package of the present invention, showing the claimed subject matter removed from the package for clarity of disclosure.

FIG. 2 is a perspective view of the package shown in an environment of use.

The features shown in broken lines depict environmental subject matter only and form no part of the claimed design.

1 Claim, 2 Drawing Sheets
(2 of 2 Drawing Sheet(s) Filed in Color)
